UNITED STATES PATENT OFFICE.

JOSIAH H. SMITH, OF PHILADELPHIA, PENNSYLVANIA, ASSIGNOR TO THE AMERICAN SUSPENSION RAILWAY COMPANY, OF PHILADELPHIA, PENNSYLVANIA.

TRUCK.

936,825.

Specification of Letters Patent.

Patented Oct. 12, 1909.

Application filed December 29, 1908. Serial No. 469,740.

To all whom it may concern:

Be it known that I, JOSIAH H. SMITH, a citizen of the United States, residing at Philadelphia, in the county of Philadelphia and State of Pennsylvania, have invented certain new and useful Improvements in Trucks, of which the following is a specification.

My invention relates to improvements in trucks, particularly designed for use on suspension railways, the object of the invention being to provide an extremely strong support for the car, which will allow of a pivotal movement of the truck and overcome swinging movement of the car.

15 A further object is to provide an improved construction of bolster having spring mounting at its ends on the side frames of the truck, and made at its center with an integral journal, constituting the car support.

20 A further object is to provide an improved construction of bolster having a central car supporting journal and enlarged rubbing surface to contact with rubbing surfaces on car supporting hangers, and prevent swinging of the car.

25 A further object is to provide an improved construction of tie-bar, which latter affords mounting for auxiliary wheels normally out of contact with the tracks, but in position to assist in supporting the truck in the event of injury to a wheel or axle, and hence prevent falling of the truck.

With these and other objects in view, the 30 invention consists in certain novel features of construction, and combinations and arrangements of parts as will be more fully hereinafter described and pointed out in the claims.

40 In the accompanying drawings, Figure 1, is a top plan view illustrating my improvements. Fig. 2, is a view in side elevation partly in section. Fig. 3, is a view in cross section on the line 3—3 of Fig. 2, and, Fig. 45 4, is a view in end elevation.

1, 1, represent the side frames provided with the ordinary yokes 2, receiving the journal box 3, supported on the axles 4, the latter secured to the ordinary wheels 5. 50 These frames 1, 1, are connected at their center by angle iron transoms 6 secured to the frames by means of the angle brackets 7, the latter, securely riveted to the transoms 6 and to the frames 1. These transoms

prevent lateral movement and buckling of 55 the side frames.

U-bolts 8 straddle the frames 1, at their lower ends, project through openings in spring plates 9, and nuts 10 are screwed on to the bolts below the plates 9. Coiled springs 11 are supported on the plates 9 and bear upwardly against spring plates 12. Bolts 13 having their upper ends countersunk in the plates 12, extend downwardly through the coiled springs 11 and plates 9, 60 and through openings in the ends of semi-elliptical springs 14, and nuts 15 are secured on the lower ends of said bolts 13 to effectually clamp the ends of the springs 14.

16, 16, represent tie-bars, which are in the form of flanged castings, having boxes 17 at their ends, secured to the lower ends of the yoke portions 2 of arms 1, by means of bolts 18, and rigidly connect the lower ends of said yokes, constituting a fixed portion of 70 the side frames. These tie-bars are provided at their center with bearings 19, in which the axle stubs 20, of auxiliary wheels 21, are mounted, and these auxiliary wheels 21 are preferably positioned, so as to be just above 75 the rails and out of contact therewith, but in such close relation to the track, that should one of the axles, or one of the wheels become broken, the auxiliary wheels will come into instant engagement with the track, 80 supporting the truck, and prevent the truck leaving the track.

22 represents my improved bolster, which comprises a single integral casting, having its ends supported at the center of the semi-elliptical springs 14, and secured thereto by 90 means of U-bolts 23. These U-bolts 23, there being two employed at each end of the bolster, are each made with one member longer than the other, the shorter member 95 only extending up through block 24 on top of the springs, and secured by nuts 25 while the longer members only of said bolts, extend up through the blocks 24, and also through the bolster ends, and are secured by 100 nuts 26. It will thus be seen that the bolts 23 secure the bolster on the springs, and the several sections of the latter together, and that only one member of each U-bolt extends through the bolster, which renders it 105 necessary to remove but four nuts 26 to disconnect the bolster from the truck, and not disturb the other elements of the truck in

the slightest. The intermediate portion of said bolster 22 is cast hollow and enlarged forming a flat rubbing plate 27, and at the center the bolster is made with a tubular post 28 which connects the upper member of the bolster and the rubbing plate to form a strong and durable structure. Below the rubbing plate at the center of the bolster, and in line with the post 28, a tubular ⁵ pending integral journal 29 is provided on the bolster, and is made with an annular enlargement or head 30 at its lower end. This journal 29 is adapted to receive the car hanger sections 31 thereon, said hanger ¹⁰ sections being made with semi-cylindrical bearings at their meeting ends, to encompass the journal, and provided with flanges 32 at their side edges, which latter are securely clamped by bolts 33, to clamp the hanger ¹⁵ around the journal, and afford a pivotal mounting thereon.

It will be observed that the head 30 is of appreciable greater diameter than the bearing in the hanger section, and hence there is ²⁰ no possibility of the hanger falling from the journal.

The hanger sections 31 are both provided with enlargements 34 constituting rubbing faces to rub against the enlargements 27 ²⁵ and prevent lateral swinging movement of the hanger sections on the bolster, and compel the springs of the truck to take up all such swinging tendency. The hanger sections 31 may be constructed in a great many ³⁰ ways, those shown straddling the car body and secured by angle brackets 36 to an I-beam 37 extending across the upper portion of the car. The extreme ends of the hanger sections are shown secured by nuts 38 to ³⁵ upright bars or rods in the car body.

By constructing improvements as above described, I provide a construction of bolster and supporting means for the car body, which will prevent any independent swinging ⁴⁰ movement of the car body on the bolster, and which will absolutely prevent any separation of the car body from the bolster; but permit a sufficient pivotal connection ⁴⁵ between them to compensate for the curvatures of the track, and the pivotal movement of the truck, and I further provide an improved construction which can be readily assembled, which will embody the maximum of strength and durability with the minimum of weight, and which will absolutely ⁵⁰ prevent accident, due to a broken wheel or axle.

A great many slight changes might be made in the general form and arrangement ⁵⁵ of parts described without departing from my invention, and hence I do not restrict myself to the precise details set forth, but consider myself at liberty to make such changes and alterations as fairly fall within ⁶⁰ the spirit and scope of my invention.

Having thus described my invention what I claim as new and desire to secure by Letters Patent is:

1. In a truck of the character described, the combination with side frames, and springs on the side frames, of a bolster supported at its ends by said springs, and an integral depending vertical car supporting journal on said bolster. ⁷⁰

2. In a truck of the character described, ⁷⁵ the combination with side frames and springs secured to said side frames, of a bolster supported upon said springs and having an integral depending journal, and car supporting hangers supported upon said journal. ⁸⁰

3. In a truck of the character described, the combination with side frames, and springs on the side frames, of a bolster supported at its ends by said springs, an integral depending car supporting journal on said bolster, and an integral head on the lower end of said journal. ⁸⁵

4. In a truck of the character described, the combination with side frames, and springs on the side frames, of a bolster supported at its ends by said springs, and constituting an open casting, an integral post in the center of said casting, and an integral journal below and in line with the post. ⁹⁰ ⁹⁵

5. In a truck of the character described, the combination with side frames, and springs on the side frames, of a bolster supported at its ends by said springs and constituting an open casting, of an integral tubular post in the center of said casting, and an integral tubular journal below and in line with the post, and an annular enlargement or head on the lower end of said journal. ¹⁰⁰

6. In a truck of the character described, ¹⁰⁵ the combination with side frames, and springs secured to the side frames, of a bolster secured at its ends on said springs and having an integral depending enlargement constituting a rubbing plate, an integral journal depending from said enlargement, car hangers having rotary mounting on said journal and in close contact with said rubbing plate, and a head on the lower end of said journal, supporting the hangers ¹¹⁰ ¹¹⁵ thereon.

7. In a truck of the character described, the combination with side frames, and springs secured thereto, of a bolster secured at its ends on said springs, an integral hollow enlargement on said bolster constituting a rubbing plate, an integral post located centrally in the bolster and connecting an upper bar with the rubbing plate, an integral depending journal at the center of the enlargement in line with said post, an enlarged head on the lower end of said journal, and car supporting means having rotary mounting on said journal above the head and constructed to rub against said rubbing plate. ¹²⁰ ¹²⁵ ¹³⁰

8. In a truck of the character described, the combination with side frames, and springs secured to said frames, of a bolster, blocks located upon said springs and upon which the ends of said bolster are disposed, two U-bolts located at each end of the bolster, each bolt having but one of its members projecting up through the bolster, nuts above the bolster on the longer ends of the U-bolts, and the shorter ends of said U-bolts extending up only through the blocks, nuts on the ends of the shorter members above the blocks, and means for supporting a car from the center of said bolster. 10
- 15 9. In a truck of the character described, the combination with side frames, axles supporting the side frames, and wheels supporting the axles, of tie bars on the side frames, axle stubs secured to the center of the tie bars projecting outward therefrom, and auxiliary wheels supported on said axle stubs and normally out of contact with the track. 20
- 10 10. In a truck of the character described, the combination with side frames, axles supporting the side frames, and wheels supporting the axles, of tie-bars on the side frames, and auxiliary wheels supported centrally in said tie-bars and normally out of contact with the track. 25
- 30 11. In a truck of the character described, the combination with side frames, yokes on said side frames, journal boxes in said yokes, axles in said journal boxes and wheels on said axles, of tie-bars, comprising castings having boxes at their ends, bolts securing said boxes to the lower ends of said yokes, and auxiliary wheels supported midway between the ends of said tie-bars, and normally out of contact with the track. 35
- 40 12. A bolster for trucks of the character described, comprising an integral casting having a central open enlargement constituting a flat rubbing surface, an integral post located centrally in the bolster and connecting the rubbing plate with an upper bar, an integral journal depending from the rubbing plate and in line with the said post, and an annular enlargement or head on the lower end of said journal. 45
- 50 13. In a device of the character described, the combination with side frames, and a truck bolster connecting the side frames, of a depending journal at the center of said bolster, an annular enlargement or head on the lower end of said journal, hanger sections, semi-cylindrical bearings at the adjacent ends of said hanger sections, bolts clamping said hanger sections about the journal and above the head thereof, and means for securing said hanger sections to a car body. 55
- 60 14. In a device of the character described, the combination with side frames, and a truck bolster connecting the side frames, of a depending journal at the center of said
- bolster, an annular enlargement or head on the lower end of said journal, hanger sections, semi-cylindrical bearings at the adjacent ends of said hanger sections, bolts clamping said hanger sections about the journal and above the head thereof, a car frame, an I-beam across the car frame, and angle brackets securing said hangers to the I-beam. 70
15. In a truck of the character described, the combination with side frames, of a bolster connecting the side frames, and a depending car supporting journal on said bolster. 75
16. In a truck of the character described, the combination with side frames, of a bolster connecting the side frames, and a depending integral car supporting journal on the center of said bolster. 80
17. In a truck of the character described, the combination with side frames, of a bolster connecting the side frames, and a depending tubular integral car supporting journal at the center of said bolster. 85
18. In a truck of the character described, the combination with side frames, of a bolster connecting the side frames, a depending car supporting journal on said bolster, and an integral head on the lower end of said journal. 90
19. In a truck of the character described, the combination with side frames, of a bolster supported at its ends by said side frames and constituting an open casting, of an integral tubular post in the center of said casting, and an integral tubular journal below and in line with the post. 95
20. In a truck of the character described, the combination with side frames, of a bolster supported at its ends by said side frames and constituting an open casting, of an integral tubular post in the center of said casting, an integral tubular journal below and in line with the post, and an annular enlargement or head on the lower end of said journal. 105
21. In a truck of the character described, the combination with side frames, of a bolster connecting the side frames and having an integral depending enlargement constituting a rubbing plate, and an integral car supporting journal depending from said enlargement. 110
22. In a truck of the character described, the combination with side frames, of a bolster having an integral depending enlargement constituting a rubbing plate, an integral journal depending from said enlargement, car hangers having rotary mounting on said journal and in close contact with said rubbing plate. 115
23. In a truck of the character described, the combination with side frames, of a bolster supported on the side frames, an integral hollow enlargement on said bolster con- 120
- 130

- stituting a rubbing plate, an integral post located centrally in the bolster and connecting the upper bar with the rubbing plate, and an integral depending car supporting journal at the center of the enlargement in line with said post.
24. In a truck of the character described, the combination with side frames, of a bolster supported on the side frames, an integral hollow enlargement on said bolster constituting a rubbing plate, an integral post located centrally in the bolster and connecting the upper bar with the rubbing plate, an integral depending car supporting journal at the center of the enlargement in line with said post, an enlarged head on the lower end of said journal, and car supporting means mounted on the journal and having a rubbing contact with said rubbing plate.
25. In a truck of the character described, the combination with side frames, a bolster connecting the side frames, a car supporting

journal on the bolster, tie bars on the side frames, and auxiliary wheels supported centrally on the outside of the tie bars and normally out of contact with the track.

26. In a truck of the character described, the combination with axles, wheels supporting the axles, journal boxes on said axles, side frames elastically supported on said boxes, tie bars on said side frames, auxiliary wheels supported centrally on said tie bars normally out of contact with the track, a bolster elastically supported on said side frames, and a car journal depending from said bolster.

In testimony whereof I have signed my name to this specification in the presence of two subscribing witnesses.

JOSIAH H. SMITH.
